Des. 184,178
Patented Dec. 30, 1958

184,178

ORNAMENTAL METALWORK PANEL

Morris Lange, Shaker Heights, Ohio

Application April 24, 1957, Serial No. 45,876

Term of patent 14 years

(Cl. D54—2)

Fig.1

I claim:

The ornamental design for an ornamental metalwork panel, substantially as shown.
